UNITED STATES PATENT OFFICE

CHARLES A. BROOKS, OF SWISSVALE, AND JOHN M. PELIKAN, OF PITTSBURGH, PENNSYLVANIA, ASSIGNORS TO THE UNION SWITCH & SIGNAL COMPANY, OF SWISSVALE, PENNSYLVANIA, A CORPORATION OF PENNSYLVANIA

RAILWAY SIGNALING

Application filed October 29, 1929. Serial No. 403,199.

Our invention relates to railway signaling, and particularly to signaling for a stretch of railway track adjacent its connection with a passing siding.

One feature of our invention is the provision of means for inter-controlling opposing signals adjacent a passing siding by apparatus requiring only two line wires.

We will describe one form of apparatus embodying our invention, and will then point out the novel features thereof in claims.

The accompanying drawing is a diagrammatic view showing one form of apparatus embodying our invention.

Referring to the drawing, the reference characters 1 and 1^a designate the rails of a stretch Y of railway track connected with rails 1^b and 1^c, respectively, of a siding Z by means of switches designated by the reference characters F¹ and F², respectively. Rails 1 and 1^a of stretch Y are divided by means of insulated joints 2 into sections A—B, B—C, C—D and D—E. Each of these track sections is provided with a track circuit including a battery 3 connected across the rails adjacent one end of the section, and a relay designated by the reference character R with a distinguishing exponent and connected across the rails adjacent the opposite end of the section.

Each of the switches F may be manually operated or may be operated by any other suitable means. Means for operating these switches form no part of our present invention, and are hence not shown in the drawing. Each switch F controls a pair of pole-changing contacts which are closed in one position when the switch is in its normal position only, and in a second position when the switch is in its reverse position only. For example, contacts 12 and 20 of switch F¹ connect with terminals 12^a and 20^a, respectively, when the switch is in its normal position, and connect with terminals 12^b and 20^b when the switch is in its reverse position.

Signals designated by the reference character S with distinguishing exponents govern traffic movements over stretch Y only, or over stretch Y to or from siding Z. Signals S¹ and S⁵ govern eastbound traffic move-

ments over stretch Y only, that is, traffic movements toward the right as shown in the drawing. Signals S³ and S⁷ similarly govern westbound traffic movements over stretch Y only. Signals S² and S⁸ govern traffic movements from stretch Y to siding Z, and signals S⁴ and S⁶ govern traffic movements from siding Z to stretch Y. As shown in the drawing, each of these signals is of the semaphore type.

Each of the signals S³ and S⁵ controls a pair of pole-changing contacts which are closed in one position when the arm of the signal is in the "stop" position or in any position between the "stop" position and the "caution" position, and which are closed in a second position when the arm of the signal is in the "caution" or the "proceed" or any intermediate position. For example, contacts 7 and 8 of signal S³ connect with terminals 6 and 5, respectively, when the arm of signal S³ is in the stop position or in any position between the stop and caution positions, and connect with terminals 5 and 4, respectively, when the arm of signal S³ is in the caution or the proceed or any intermediate position.

Signals S¹ and S⁷ are controlled by polarized signal relays designated by the reference character L with distinguishing exponents. Relays L are controlled by main relays designated by the reference character H with distinguishing exponents, and which may be controlled in any suitable manner, such, for example, as by means of levers located in a train dispatcher's office. The means for controlling relays H form no part of our present invention, and are therefore not shown in the drawing.

Relays L² and L¹ are also controlled by the pole-changing contacts of switches F, and by track relays R, and by the pole-changing contacts of signals S³ or S⁵, respectively, when switches F¹ and F² are in the normal position.

Current for energizing relay L¹ is supplied by a battery Q² located adjacent signal S⁵. Current for energizing relay L² is supplied by battery Q¹ located adjacent signal S³.

Resistance N¹ and N² are connected in se-

ries with batteries Q^1 and Q^2 to prevent short-circuiting these batteries under certain conditions which will be hereinafter explained.

As shown in the drawing, all parts are in their normal condition, that is, each of the track sections is unoccupied, each relay H is de-energized, each relay L is de-energized, each signal S is indicating "stop", and each of the switches F is in its normal position.

10 We will now assume that the dispatcher desires to clear signal S^7 . He therefore energizes relay H^2 . Relay H^2 , upon becoming energized, completes a circuit for relay L^2 passing from battery Q^1 , through resistance

15 N^1 , contact 5—8 of signal S^3 , contact 21^b of relay H^1 , contact 20^a—20 of switch F^1 , contact 19—19^a of switch F^2 , contact 18^a of relay H^2 , winding of relay L^2 , contact 17^a of relay H^2 , contact 16 of relay R^4 , contact

20 15^a—15 of switch F^2 , contact 14 of relay R^3 , contact 13 of relay R^2 , contact 12—12^a of switch F^1 , contact 11 of relay R^4 , contact 10^b of relay H^1 , wire 9, and contact 7—6 of signal S^3 back to battery Q^1 . Relay L^2 is energized in the reverse direction by this circuit, causing the arm of signal S^7 to be operated to the "caution" position by its circuit passing from battery Q^2 , through contact 22 of relay L^2 , and the mechanism of signal S^7 back

25 to battery Q^2 .

If the arm of signal S^3 is now moved to its "caution" or its "proceed" position, pole-changing contacts 7 and 8 of signal S^3 will be moved to connect with terminals 5 and 4, 35 and current supplied by battery Q^1 will, therefore, now flow in the opposite direction through the circuit already traced for relay L^2 , causing relay L^2 to become energized in the normal direction. The arm of signal S^7 will then be operated to its "proceed" position by its circuit passing from battery Q^2 , through contacts 22 and 23 of relay L^2 , and the mechanism of signal S^7 back to battery Q^2 .

45 If, when the arm of signal S^7 is in its "caution" or its "proceed" position, an eastbound train should overrun signal S^1 , not stopping until it had entered section A—B, the circuit already traced for relay L^2 would be opened at contact 11 of relay R^1 , causing relay L^2 to be de-energized and the arm of signal S^7 to, therefore, be returned to its "stop" position. A westbound train passing signal S^7 at "caution" or "proceed" would similarly cause the arm of signal S^7 to be returned to its "stop" position by opening contact 16 of relay R^4 . The westbound train then continuing toward point A would keep relay L^2 de-energized by de-energizing relays R^3 , R^2 and R^1 , successively.

We will next assume that switch F^1 is in its reverse position, and that switch F^2 is in its normal position, and that the dispatcher again energizes relay H^2 . A second circuit 65 for relay L^2 is thereby completed passing

from battery Q^1 , through resistance N^1 , contact 20^b—20 of switch F^1 , contact 19—19^a of switch F^2 , contact 18^a of relay H^2 , winding of relay L^2 , contact 17^a of relay H^2 , contact 16 of relay R^4 , contact 15^a—15 of switch F^2 , contact 14 of relay R^3 , contact 13 of relay R^2 , and contact 12—12^a of switch F^1 back to battery Q^1 . Relay L^2 is now energized in the reverse direction, and hence the arm of signal S^7 moves to its "caution" position. If, now, an eastbound train enters section A—B, the circuit just traced for relay L^2 will not be affected thereby, and hence signal S^7 will continue to indicate "caution".

We will now assume that all parts are again in their normal condition, and that the dispatcher then energizes relay H^2 , and that the arm of signal S^3 is moved to its "caution" or its "proceed" position, causing the arm of signal S^7 to again occupy its "proceed" position. We will further assume that the dispatcher then desires to return the arm of signal S^7 to its "stop" position before a train arrives. He therefore de-energizes relay H^2 , causing the back contacts 17^b and 18^b of relay H^2 to be closed. As long as the arm of signal S^3 is in its "caution" or its "proceed" position or any intermediate position, a circuit will be completed passing from battery Q^1 , through resistance N^1 , contact 5—7 of signal S^3 , wire 9, contact 10^b of relay H^1 , contact 11 of relay R^1 , contact 12^a—12 of switch F^1 , contact 13 of relay R^2 , contact 14 of relay R^3 , contact 15—15^a of switch F^2 , contact 16 of relay R^4 , contact 17^b of relay H^2 , contact 28—25 of signal S^5 , battery Q^2 , resistance N^2 , contact 26—27 of signal S^5 , contact 18^b of relay H^2 , contact 19^a—19 of switch F^2 , contact 20—20^b of switch F^1 , contact 21^b of relay H^1 , and contact 8—4 of signal S^3 back to battery Q^1 . The use of resistances N^1 and N^2 prevents short-circuiting of batteries Q^1 and Q^2 by the circuit just traced.

The control of signal S^1 for eastbound moves is similar to that already described for signal S^7 for westbound moves, and will therefore be readily understood without further explanation.

It is evident that if both switches F^1 and F^2 are reversed, or if both relays H are energized at the same time, no current can reach either relay L^1 or L^2 , and hence neither of these relays will be energized, and therefore neither signal S^1 nor signal S^7 will clear.

From the foregoing description and the accompanying drawings, it is clear that with apparatus embodying our invention, the inter-control of two opposing signals, such as signals S^1 and S^7 at a passing siding, is effected with the use of only two line wires extending between these two signals. It is evident that signals S^2 and S^8 can be similarly inter-controlled.

Although we have herein shown and described only one form of apparatus embody-

ing our invention, it is understood that various changes and modifications may be made therein within the scope of the appended claims without departing from the spirit and scope of our invention.

5 Having thus described our invention, what we claim is:

1. In combination, a stretch of railway track, a signal adjacent one end of said stretch, a second signal adjacent the other end of said stretch, a main relay, a second main relay, a signal relay, a second signal relay, a pole-changer, a second pole-changer, a circuit for said first signal relay including 10 a front contact of said first main relay and a back contact of said second main relay as well as said second pole-changer and a source of current and the winding of said first signal relay in series, a circuit for said second signal relay including a front contact of said second main relay and a back contact of said first main relay as well as said first pole-changer and a second source of current and the winding of said second signal relay in 15 series, means controlled by said first signal relay for controlling said first signal, and means controlled by said second signal relay for controlling said second signal.

2. In combination, a stretch of railway track including a switch, a signal adjacent one end of said stretch, a second signal adjacent the other end of said stretch, a main relay, a second main relay, a pole-changer, a signal relay, a second signal relay, a normal switch contact closed when said switch is in its normal position only, a reverse switch contact closed when said switch is in its reverse position only, a circuit for said first signal relay including a front contact of said 20 first main relay and a back contact of said second main relay as well as a source of current and said normal switch contact, a circuit for said second signal relay including a front contact of said second main relay and a back contact of said first main relay as well as said normal switch contact and said pole-changer and a second source of current, a second circuit for said second signal relay including a front contact of said second main relay and said reverse switch contact and said second source of current, means controlled by said first signal relay for controlling said first signal, and means controlled by said second signal relay for controlling 25 said second signal.

3. In combination, a stretch of railway track including a switch, a signal adjacent one end of said stretch, a second signal adjacent the other end of said stretch, a main relay, a second main relay, a signal relay, a second signal relay, a normal switch contact closed when said switch is in its normal position only, a reverse switch contact closed when said switch is in its reverse position only, a circuit for said first signal relay including 30

a front contact of said first main relay and a back contact of said second main relay as well as a source of current and said normal switch contact, a circuit for said second signal relay including a front contact of said second main relay and a back contact of said first main relay as well as said normal switch contact and a second source of current, a second circuit for said second signal relay including a front contact of said second main relay and said reverse switch contact and said second source of current, means controlled by said first signal relay for controlling said first signal, and means controlled by said second signal relay for controlling 35 said second signal.

In testimony whereof we affix our signatures.

CHARLES A. BROOKS.
JOHN M. PELIKAN.
